[57] **CLAIM**

The ornamental design for a "cable clip and fastener combination", as shown and described.

DESCRIPTION

FIG. 1 is a top perspective view of a cable clip and fastener combination, showing a first embodiment of my new design; FIG. 2 is a side elevational view thereof, the opposite side being a mirror image of that shown;

FIG. 3 is a left end elevational view thereof;

FIG. 4 is a right end elevational view thereof;

FIG. 5 is a top plan elevational view thereof;

FIG. 6 is a bottom plan view thereof;

FIG. 7 is a top perspective view of a cable clip and fastener combination, showing a second embodiment of my new design;

FIG. 8 is a side elevational view thereof, the opposite side being a mirror image of that shown;

FIG. 9 is a left end elevational view thereof;

FIG. 10 is a right end elevational view thereof;

FIG. 11 is a top plan elevational view thereof; and,

FIG. 12 is a bottom plan view thereof.
